UNITED STATES PATENT OFFICE

ALBERT C. MEYER, OF SAN DIEGO, CALIFORNIA

CALCULATOR

Application filed May 4, 1926. Serial No. 106,633.

My invention relates to calculators or calculating machines, more particularly adapted for calculating percentages of principals as in computing interest, or for calculating 5 multiples of certain base numbers, such as in computing costs and the like.

The objects of my invention are: first, to provide a calculating machine having a long tape provided with tabulations adapted to be 10 wound in opposite directions on drums by a handle adapted to be rotated in one direction only, thereby preventing the tape from being unwound from one drum when not, at the same time, wound on another; second, to 15 provide a novel gear mechanism and gear shifting means for connecting the drum rotating handle with one or the other of a pair of drums upon which a long tabulation tape is wound; third, to provide novel means for 20 changing the connection of the tape operating handle with the tape supporting drums whereby, when the connection is changed, the direction in which the tape is adapted to be shifted will be indicated on the handle of 25 the shifting means; fourth, to provide a positive tape stop means whereby the tape is prevented from being unwound from either supporting drum without unnecessary strain on the tape itself; fifth, to provide means in 30 connection with a machine of this class for holding the tape taut at all times; sixth, to provide a calculator having a tabulation tape mounted on the drum in such a manner that a minimum of friction and tension is applied 35 and exerted on the tape when passing from one drum to the next; seventh, to provide means in connection with the drums of a calculator of this class for yieldably holding the tape in alinement on the drums by yield- 40 able direction means at the edges of the tape; eighth, to provide a calculator of this class having a long calculating tape or strip which, even though the tape or strip shrinks or expands under different weather conditions, 45 correct readings and calculations may nevertheless be made without taking into consideration the shrinking or expansion of the tape or strip; ninth, to provide a calculator having a 50 long tabulation strip mounted on drums in a manner to be wound from one to the other,

the supporting frame having indices contiguous to the face of the tape adapted to align with prominent characterizations or indications on the face of and extending longitudinally with the tape, whereby the drums may 55 be rotated rapidly but still indicate to the operator the approximate location on the tape of the tabulation desired for a particular calculation; tenth, to provide a calculating means having a tabulation provided with sets of characters representing principals and percentages thereof or numbers and multiples thereof and a slide in connection with the tabulation, the slide having a portion through which a set or a portion of a 60 set of the characters or numbers may be viewed; eleventh, to provide a novel spacing-off means in connection with the slide of a calculating means for spacing off horizontally arranged characters or 65 numbers; twelfth, to provide a calculating means of this class having a triple set of slides mounted over a tabulation so that one of the slides or the calculation slide may be readily shifted to any portion of the tabula- 70 tion for calculating interest, percentages, costs and the like; thirteenth, to provide calculating machines having a tabulation provided with a vertical column of horizontally 75 arranged numbers, the numbers at the left being offset relatively to those at the right 80 so that two distinct sets of numbers may be provided in close relation on the same tabulation; fourteenth, to provide a calculating means of this class having a tabulation of 85 the type mentioned and a slide in connection with and shiftable over said tabulation, said slide being provided with a portion for viewing the numbers and also with zeros for extending the value of the group of numbers at 90 one side of the column; fifteenth, to provide a tabulation and slide combination, as mentioned, in which the slide is provided with another shiftable calculating slide uncovering 95 and covering said zeros and for correspondingly increasing and decreasing the value of the group of numbers at the opposite side of the column, said latter slide carrying means for spacing off decimals and thousands and millions in the two groups of numbers; six- 100

teenth, to provide as a whole a novelly constructed, arranged and operated calculator, and seventeenth, to provide a calculator which is simple and economical of construction proportionate to its functions, durable, efficient, reliable, adapted for many classes of calculations, and which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters of reference thereon, which form a part of this application, in which:

Figure 1 is a top plan view of my calculator in one form of construction; Fig. 2 is a side view thereof, taken from the operating handle side, with the outer casing broken away and in section to facilitate the illustration; Fig. 3 is a sectional elevational view thereof, taken through 3—3 of Fig. 1; Fig. 4 is a sectional view thereof, taken through 4—4 of Fig. 3, showing certain parts and portions thereof broken away and in section to facilitate the illustration; Fig. 5 is an enlarged fragmentary top view of the calculating slide in position over a fragmentary portion of the tabulation tape; Fig. 6 is a fragmentary sectional elevational view thereof, taken through 6—6 of Fig. 5; 7 is a view similar to that of Fig. 5, showing a slightly modified arrangement of the numbers in the tabulation tape and a corresponding modification in the calculating slide, and Fig. 8 is a fragmentary view of a portion of the tabulation tape for computing interest on principal.

Like characters of reference refer to similar parts and portions throughout the several views of the drawings.

The supporting frame of my calculator consists essentially of the base member 1, the inner frame 2 and the outer casing 3 enclosing the mechanism and provided at the upper end with a removable cover 3a having an opening 3b therein. The inner frame 2 consists of a pair of spaced side plates 2a and 2b secured to the base member 1 and tied and spaced relatively to each other by a plurality of tie rods 2c.

On and between the plates 2a and 2b is revolvably mounted a pair of spaced and axially parallel shafts 4 and 5 on which are mounted, respectively, drums 6 and 7, which drums are secured to their respective shafts. On said shafts and against the ends of the drums are positioned tape directing flanges 8, which are yieldably held against the ends of the drums by means of compression springs 9 positioned between said flanges and the plates of the frame 2. Around the drums 6 and 7 are wound the opposite ends of the tabula-

tion or calculation tape 10, which is secured at its ends in any convenient manner to the drums, as shown best in Fig. 3.

The shafts 4 and 5 are held in position on the plates 2a and 2b of the frame 2 by means of collars 11 at one of their ends and by means of spur gears 12 and 13, respectively, at their opposite ends. Against the outer side of the plate 2b is positioned and reciprocally mounted a gear shifting and supporting slide 14, said slide being mounted on a pair of brackets 15 at its opposite ends. Said slide is positioned around the shafts 4 and 5 and between the plate 2b and gears 12 and 13. Intermediate the ends of the slide 14 is revolvably mounted a large drive gear 16, which is adapted to mesh with either of the gears 22 or 13. On the spindle 17, on which the gear 16 is revolvably mounted, is also revolvably mounted the drum operating handle 18. At the inner side of the crank portion of the handle 18, contiguous to its axis, is pivotally mounted a pawl 19, which is adapted to engage the teeth of the ratchet 20 secured to the outer side of the gear 16 around its axis, the pawl 19 being forced into engagement with the teeth of the ratchet by a spring member 21, as shown best in Fig. 4. Thus, the gear 16 is adapted to be driven in one direction only by the operating handle 18, which direction is in that of the arrow shown in Fig. 2. The drive gear 16 is adapted to rotate the gear 12 through an intermediate gear 22 revolvably mounted on the plate 2b of the frame. Thus, when the drive gear 16 is shifted into engagement with either the gear 22 for rotating the gear 12 or into mesh with the gear 13, the rolls or drums 6 and 7 are permitted only to wind the tape onto the drums; and at no time is the tape permitted to be unwound and pile up unless wound on the other drum.

The means for shifting the slide 14 consists of a rod 23 rotatably mounted near its opposite ends on the two plates 2a and 2b of the frame 2, the one end of the rod 23 extending through the plate 2b being provided with a crank arm 23a having a pin 23b at its outer end, which pin is adapted to operate in a transverse slot 14a at the outer end of an offset portion 14b at the rear end of the slide 14. The opposite end of the rod 23 extends through the wall of the outer casing 3 and is provided at said end with a handle 24 having a laterally extended wing 24a provided at its opposite sides with arrows 24b directed from the axis of the rod 23. These arrows on the handle 24 indicate the direction in which the tape 10 is adapted to be shifted when the operating handle 18 is rotated. The slide shifting rod 23 is fixed longitudinally by the crank arm 23a engaging the outer side of the plate 2b, and by means of a collar 25 engaging the outer side of the other plate. Said collar 25 is flattened at its opposite sides, as shown best in Fig. 3. Against the flattened

sides of said collar are positioned the free ends of leaf springs 26 supported by the plate 2a, which leaf springs are adapted to serve as a yieldable locking means for holding the gear shifting handle 24 and therefore the slide 14 in its extreme shifted positions.

On and between the two plates of the frame 2, near their rear and lower portions, is revolubly mounted a stop screw 27, which is provided at its one end with a gear 28 adapted to be driven by the gear 12 through an intermediate gear 29, as shown in Figs. 2 and 4. On the stop screw 27 is mounted a traveling stop member 30, which is guided and prevented from rotating more than one revolution with the screw 27 by a guide rod, which in this case is one of the tie rods of the frame, as shown in Figs. 2 and 4. Near the opposite ends of the screw 27 are provided pairs of lock nuts 31 or any other suitable means for limiting the stop member 30. Thus, when the gear 16 is shifted, as shown in Fig. 2, and the handle 18 rotated in the direction of the arrow, the screw 27 will be rotated through the gearing and feed the stop member 30 towards one of the pairs of lock nuts 31. When the stop member 30 engages the lock nuts, sufficient resistance is applied to the rotation of the handle 18 as to prevent, or at least give sufficient warning to prevent, the handle from being rotated farther so as to prevent the tape 10 from being unwound from the drum 7. When the gear 16 is shifted in mesh with the gear 13 and the handle 18 rotated, the stop member 30 will travel in the opposite direction on the screw and stop the rotation of the handle 18 through the tape itself but in a similar manner.

Within the casing 3 and below the opening 3b in the cover 3a thereof is positioned a plate 32 over which the tape is adapted to be drawn. This plate is adjustably supported at its under side and at its lateral ends on a pair of brackets, 33 which are adjustably mounted in a vertical direction on the side plates of the frame 2. At the forward and rear edges of the plate 32 are revolubly mounted long rollers 34, which are supported at their ends on brackets secured to the under side of the plate 32. The axes of the rollers 34 are parallel with those of the drums 6 and 7, thus permitting the tape to pass freely from one drum, over the rollers 34 and plate 32 onto the other drum, it being noted that the upper portions of the rollers 34 extend slightly above the upper or normally outer surface of the plate 32.

The plate 32 is also provided with other downwardly extending brackets 35, at the lower ends of which are pivotally mounted one of the ends of auxiliary roller supporting arms 36. These arms are bifurcated at their outer ends and revolubly support between the furcations thereof auxiliary rollers 37. There are preferably provided four of such

auxiliary rollers, two extending forwardly of the foremost roller 34 and two extending backwardly from the rearmost roller 34. Said auxiliary rollers are yieldably held in engagement with the under side of the tape 10 by means of tension springs 38 secured at one of their ends to a lug 33a on the under side of the plate and at their opposite ends to the arms 36. Thus, the tape is held taut at all times between the drums and on the drums and at the same time always wound straight onto the drums, the latter function being facilitated by the resilient action of the flanges 8 relatively to the ends of the drums.

Over the opening 3b of the outer casing cover 3a is positioned a transparent plate 39, which is secured in position by a rectangular frame 40, which extends preferably over the front and rear edges of the plate only. At the forward and rear sides, or as will be referred to hereafter, the upper and lower sides of the frame 40 are provided transverse channels 40a in which are positioned the upper and lower ends or edges of the rectangularly shaped slide 41 for guiding said slide transversely relatively to the casing and the tabulation on the tape 10. Between and on the lateral side portions 41a of the slide 41, is reciprocably mounted another slide 42, which is provided at its upper or outer side with an open portion 42a. The lower portion of the slide 42, which consists preferably of a separate member 43 for retaining the upper portion of the slide 42 on the side portions 41a of the slide 41, is provided with a pair of openings 43a and 43b opposite or below the opening 42a. The opening 43a is positioned below and to the left of the opening 43b and is adapted to permit the first two digits of the principal on the tabulation of the tape to be seen therethrough, the other opening 43b being sufficiently long to permit all of the numbers or digits of the corresponding interest of the principal to be seen therethrough. At the upper side of the member 43, is provided a longitudinal channel 43c in which is reciprocably mounted another slide 44, which is also open at its middle portion, as indicated by 44a. The slide 44 is adapted to be driven back and forth or from one side to the other by means of a knob 45 secured to an arm 46 intermediate the ends thereof, which arm is positioned within a backwardly extending bracket portion 42b of the slide 42 and is pivotally mounted at its rear end on a pivot pin 47 within said bracket portion. The forward end of the arm 46 is pivotally connected to a slotted portion 44b extending upwardly from the slide 44 and backwardly into the bracket portion 42b. The knob 45 extends through an arcuate slot 42c at the upper side of the bracket portion 42b and is adapted to be shifted to the leftmost position in said slot by a spring member 48

secured to the pivot pin 47 at its one end and connected to the arm 46 at its opposite end, as shown best in Fig. 5.

The tabulations shown on the tape in the drawings are for computing interest of principals at various rates. On the tape shown in Figs. 1, 5 and 8 are provided two distinct sets of figures or numbers, those at the left of each column consisting of two digits, being preferably printed with a different colored ink from the remaining seven digits at the right side of each column. As shown in Figs. 1 and 8, the numbers or digits at the left side of each column are offset a whole line below those at the right, therefore, interest of a certain principal will be found above the line of the first two digits representing the principal. Said digits representing the principal may be viewed through the opening 43a in the slide 43. The remaining digits, in the form of zeros, are inscribed or otherwise applied to the slide 43 immediately to the right of the opening 43a, as indicated by 43d, there being shown seven zeros on the slide 43 in Fig. 5 of the drawings. The righthand end of the portion of the opening 44a of the slide 44 opposite the opening 43b of the slide 43 extends a greater distance to the right than the portion of the opening 44a opposite the opening 43a or the zeros on the slide 43 to make the ends of the interest and principal sums correspond. On the slide 44 is mounted a plurality of arm 44c, 44d, 44e and 44f, the former, 44c and 44d, extending upwardly or forwardly from the lower edge of the opening 44a, and the latter extending downwardly or backwardly from the forward edge of said opening. At the end of the arm 44c is provided an inscription or indication representing a decimal point between the dollars and cents of the principal sum; this decimal point may be shifted to divide the zeros on the slide 43 as well as the digits on the tape. At the ends of the other arms 44d, there being provided one or more, are provided indications representing commas to space off thousands and millions of dollars in the principal sum. At the end of the arm 44e is also provided a period for indicating the decimal point between the dollars and cents of the interest sum. At the ends of the other arms 44f are provided indications representing commas to space off the thousands and millions in the interest sum.

When it is desired to compute the interest on a certain principal sum at a certain rate, the handle 18 is rotated until the proper table of principal and interest is opposite the opening 3b of the outer casing. The slides 41 and 42 are then shifted so that the openings 43a and 43b are over the desired numbers of the table or tabulation. In Fig. 5 the first two digits of the principal sum are 6 and 9, said digits being viewed through the opening 43a.

The slide 44 is then shifted so that the decimal at the end of the arm 44c spaces off the proper number of dollars in the principal sum, the principal sum shown in Fig. 5 being \$6,900.00. The interest for this sum at 6% for one month will be found to be \$034.50. If the interest for \$6.90 is desired for the same rate and term, the slide 44 is shifted to the left until the decimal point at the end of the arm 44c is between the 6 and 9. The decimal point at the end of the arm 44e will be correspondingly shifted to the left. Thus, the table shows that the interest on \$6.90 is \$0.03. In order to obtain the interest for \$6,969.69 at the same rate and term, the interest reading is first taken as shown in Fig. 5, and the interest reading recorded, then the slide is shifted two spaces to the left with the decimal point after the 9 of \$69 and the interest reading again taken and recorded below the previous reading, then the slide 44 is again shifted two spaces to the left with the decimal point positioned in front of the 6 of \$69 and the reading taken. The latter reading will show no interest of any value for 69¢ for one month at 6%. Summing up the readings, the interest for \$6,969.69 for one month at 6% will be found to be \$34.84. Any other interest for any other period at any other rate on the tape may be likewise determined.

In the modified form of construction, shown in Fig. 7, the whole principal sums are shown alternated with the interest sums in a vertical column or in columns. By reason of the change of the principal and interest sums in the column and the shifting of said sums in alinement, the opening 44a in the slide 44 is correspondingly changed. In this modified structure the decimals between the dollars and cents of the principal and interest sums are positioned in alinement and therefore mounted on the same bar 44g. The commas spacing off the thousands and millions are also mounted on the same corresponding bars 44h. The computation with the latter construction is substantially identical with that previously described.

Although each group of numbers or tabulation 10a, giving the interest on a principal sum at a certain rate for a certain period, is designated in large characters 10b at the right by the period and rate, such indication or characterization or identification cannot be easily read when the operating handle 18 is rotated at normal speed. To overcome this difficulty, there are provided on the lower or upper ledge, or both, of the frame 40, indices indicating rates of interest, such as 2%, 3% and so forth, which are adapted to aline with permanent indications 10c, such as black ink rulings, which extend longitudinally with the tape between the several groups of like tabulations. As shown in the tape in Fig. 8, such permanent indications or rulings are for cer-

tain rates only and correspond with rate indices on the frame 40. If desired these indices, as well as the rulings or other indications on the tape, may be for days, months, 5 years, or for any other item desired. Thus, when the handle 18 is rotated at a normal or rapid rate of speed and the black ink ruling 10c is opposite a certain rate index on the frame, such as 6% in Fig. 1, it will be known 10 to the operator that the 6% interest group is opposite the opening in the casing.

Although I have referred to principals, interest, rates of interest and terms of time, it will be noted that my calculator is applicable 15 for computing costs or adapted for other similar use; and although I have shown and described a particular construction, combination and arrangement of parts and portions and a certain modification thereof, I do not 20 wish to be limited to this particular construction, combination and arrangement, but desire to include in the scope of my invention, the construction, combination and arrangement substantially as set forth in the 25 appended claims.

Having thus described my invention, what I claim as new and desire to secure by Letters Patent is:

1. In a calculating means, a tabulation 30 having a plurality of distinct groups of characters positioned side by side, the characters in a group being arranged in horizontal and vertical lines, a slide reciprocably mounted over said tabulation, and adapted to frame 35 any one group of characters, a second slide reciprocably mounted on said first slide at right angles to its movement, and movable from end to end of the respective group, and a third slide reciprocably mounted on the 40 second slide in a direction parallel with the horizontally arranged characters of said respective group.

2. In a calculating means, a tabulation 45 having a plurality of distinct groups of characters positioned side by side, the characters in a group being arranged in horizontal and vertical lines, a slide reciprocably mounted over said tabulation and adapted to frame 50 any one group of characters, a second slide reciprocably mounted on said first slide at right angles to its movement, and movable from end to end of the respective group, and a third slide reciprocably mounted on the 55 second slide in a direction at right angles to its movement.

3. In a calculating means, a tabulation 60 having vertically and horizontally arranged characters, a slide reciprocably mounted over said tabulation, a second slide reciprocably mounted on said first slide at right angles to its movement, and a third slide reciprocably mounted on the second slide in a direction 65 parallel with the horizontally arranged characters of said tabulation, said third slide having an open portion through which related

characters occupying more than one line of said respective group may be viewed.

4. In a calculating means, a tabulation having vertically and horizontally arranged characters, in which related characters occupy different lines, a slide reciprocally mounted over said tabulation, adapted to frame certain groups of said characters, a second slide reciprocally mounted on said first slide at right angles to its movement, 70 and adapted to frame certain characters of said framed groups and a third slide reciprocally mounted on the second slide in a direction at right angles to its movement, said third slide having an open portion for exposing specific related characters occupying 75 said different lines.

5. In a calculating means, a tabulation having vertically and horizontally arranged characters, in which the related characters 80 occupy different lines, a slide reciprocal in a direction parallel with the horizontally arranged characters of said tabulation, means for supporting said slide over any portion of said tabulation, said slide having an open 85 portion exposing specific portions of said related characters occupying different lines, said slide having also spacing-off means over said open portion for simultaneously spacing off 90 said specific, related characters.

6. In a calculating means, a tabulation having vertically and horizontally arranged characters, in which related characters occupy different lines, a slide reciprocally mounted over said tabulation, adapted to 100 frame certain groups of said characters, a second slide reciprocally mounted on said first slide at right angles to its movement, and adapted to frame certain characters of said framed group, and a third slide reciprocally mounted on the second slide in a direction at right angles to its movement, said third slide having an open portion for exposing specific portions of said related characters occupying different lines, said third slide having also spacing-off means over said open portion for simultaneously spacing off 105 said specific, related characters.

7. In a calculating means, a tabulation having sets of characters representing certain principals and multiples in ten thereof and certain percentages thereof, a slide reciprocally mounted over said tabulation, and another slide reciprocally mounted on said first slide, said other slide having an open 115 portion through which a set or a portion of a set of said characters may be viewed, said other slide having also spacing-off means over said open portion for spacing off characters of each set in their correct relation.

8. In a calculating means, a tabulation having sets of characters representing principals and percentages thereof, and a slide reciprocally mounted over said tabulation, said slide having a restricted open portion 120

70

- through which a limited set or a limited portion of a set of said characters may be viewed, said slide having also spacing-off means over said portion for spacing off characters of each set. 70
8. In a calculating means, a tabulation having numbers and multiples thereof, and a slide reciprocally mounted over said tabulation, said slide having a restricted open portion through which a limited set or limited portion of a set of said numbers and multiples thereof may be viewed and also having spacing-off means over said portion for spacing off numbers of each set. 75
15. In a calculating means, a tabulation having a vertical column of horizontally arranged numbers, the numbers at the left being offset relatively to those at the right, a slide shiftable over said tabulation and provided with an open portion for viewing said numbers and also provided with zeros for extending the value of the group of numbers at one side of said column, and another slide reciprocally mounted on the first slide for uncovering and covering said zeros and for correspondingly increasing and decreasing the value of the group of numbers at the opposite side of the column. 80
20. In a calculating means, a tabulation having a vertical column of horizontally arranged numbers, the numbers at the left being distinguishably different from those at the right and offset relatively to the latter to the next adjacent row of horizontally arranged numbers, a slide shiftable over said tabulation and provided with an open portion for viewing said numbers and also provided with zeros for extending the value of the group of numbers at one side of said column, another slide reciprocally mounted on the first slide for uncovering and covering said zeros and for correspondingly increasing and decreasing the value of the group of numbers at the opposite side of the column, and means in connection with said other slide for spacing off decimals and thousands and millions in said two groups of numbers. 85
30. In a calculating means, a tabulation having a vertical column of horizontally arranged numbers, the numbers at the left being offset relatively to those at the right, a slide shiftable over said tabulation and provided with an open portion for viewing said numbers and also provided with zeros for extending the value of the group of numbers at one side of said column, another slide reciprocally mounted on the first slide for uncovering and covering said zeros and for correspondingly increasing and decreasing the value of the group of numbers at the opposite side of the column, and means in connection with said other slide for spacing off decimals and thousands and millions in said two groups of numbers. 90
45. In a calculating means, a tabulation having closely associated superimposed numbers and multiples thereof arranged in single columns, a slide reciprocally mounted over said tabulation, said slide having an enclosed unobstructed portion through which a set or portion of an associated set of numbers and multiples may be viewed, said slide also having spacing off means over said unobstructed portion for spacing off said numbers and multiples. 95
50. In a calculating means, the combination with a tabulation of a slide provided with an opening therein, and another slide reciprocally mounted relatively thereto, provided with a plurality of variable shaped openings movable in relative relation with the openings in said first slide, whereby characters of said tabulation may be segregated into offset relation in their relative horizontal rows of the characters of said tabulation. 100
55. In a calculating means, the combination with a tabulation of a slide provided with an opening therein, and another slide reciprocally mounted relatively thereto, provided with a plurality of variable shaped openings movable in relative relation with the openings in said first slide, whereby characters of said tabulation may be segregated into offset relation in their relative horizontal rows of the characters of said tabulation, and means for adjusting and shifting one of said slides relatively to the other. 105
60. In a calculating means, the combination with a tabulation of a slide provided with an opening therein, and another slide reciprocally mounted relatively thereto, provided with a plurality of variable shaped openings movable in relative relation with the openings in said first slide, whereby characters of said tabulation may be segregated into offset relation in their relative horizontal rows of the characters of said tabulation, means for adjusting and shifting one of said slides relatively to the other and characters positioned in relation to said openings on one of said slides forming points of segregation in the rows of figures on said tabulation. 110
65. In a calculating means, a tabulation having closely associated groups of characters in vertical and horizontal rows, a slide member provided with an opening centrally therein, adapted to expose a pair of horizontal rows of said tabulation, and another slide provided with a plurality of openings adapted to be moved into position to be seen through the opening in the first mentioned slide, some of said openings being jogged and offset, whereby the characters in the horizontal rows seen through said openings in both of said slides are varied as to length. 115
70. In a calculating means, a tabulation having closely associated groups of characters in vertical and horizontal rows, a slide member provided with an opening centrally therein, adapted to expose a pair of horizontal rows of said tabulation, and another slide provided with a plurality of openings adapted to be moved into position to be seen through the opening in the first mentioned slide, some of said openings being jogged and offset, whereby the characters in the horizontal rows seen through said openings in both of said slides are varied as to length. 120
75. In a calculating means, a tabulation having closely associated groups of characters in vertical and horizontal rows, a slide member provided with an opening centrally therein, adapted to expose a pair of horizontal rows of said tabulation, and another slide provided with a plurality of openings adapted to be moved into position to be seen through the opening in the first mentioned slide, some of said openings being jogged and offset, whereby the characters in the horizontal rows seen through said openings in both of said slides are varied as to length. 125
80. In a calculating means, a tabulation having closely associated groups of characters in vertical and horizontal rows, a slide member provided with an opening centrally therein, adapted to expose a pair of horizontal rows of said tabulation, and another slide provided with a plurality of openings adapted to be moved into position to be seen through the opening in the first mentioned slide, some of said openings being jogged and offset, whereby the characters in the horizontal rows seen through said openings in both of said slides are varied as to length. 130

tal rows of said tabulation, and another slide provided with a plurality of openings adapted to be moved into position to be seen through the opening in the first mentioned slide, some of said openings being jogged and offset, whereby the characters in the horizontal rows seen through said openings in both of said slides are varied as to length, vertical bars separating the openings in the second mentioned slide and period and comma means positioned on said vertical bars for designating the character of the points, the characters in the horizontal rows are divided into.

19. In a calculating means, a tabulation having closely associated groups of characters in vertical and horizontal rows, a slide member provided with an opening centrally therein, adapted to expose a pair of horizontal rows of said tabulation, and another slide provided with a plurality of openings adapted to be moved into position to be seen through the opening in the first mentioned slide, some of said openings being jogged and offset, whereby the characters in the horizontal rows seen through said openings in both of said slides are varied as to length, vertical bars separating the openings in the second mentioned slide, and period and comma means positioned on said vertical bars for designating the character of the points, the characters in the horizontal rows are divided into, and means in connection with both of said slides for adjusting and shifting the relative position of said slides.

35 In testimony whereof, I have hereunto set my hand at San Diego, California, this 17th day of April 1926.

ALBERT C. MEYER.
